DIAPHRAGM PUMP

Elmer H. Herbert, Oakland, Calif., assignor to
 Oliver United Felters Incorporated, Oakland,
 Calif., a corporation of Nevada

Application November 1, 1943, Serial No. 508,528

4 Claims. (Cl. 103—152)

This invention relates to a diaphragm pump, and has for one of its objects the provision in a pump of this type of a pair of solenoid-operated diaphragm valves for controlling the inlet and outlet of the pump chamber.

The invention possesses other advantageous features, some of which with the foregoing will be set forth at length in the following description where that form of the invention which has been selected for illustration in the drawing accompanying and forming a part of the present specification is outlined in full. In said drawing, one form of the invention is shown, but it is to be understood that it is not limited to such form, since the invention as set forth in the claims may be embodied in a plurality of forms.

The single figure of the drawing is a mid-vertical section taken through a pump embodying the objects of my invention, and in which the solenoids, the clock, and their circuits are diagrammatically illustrated.

The pump as shown in the drawing comprises a main chamber generally designated by the reference numeral 1, formed by two opposed dished castings 2 and 3 bolted together along their respective peripheral flanges 4 and 5. Clamped between and sealed to the flanges 4 and 5 is a flexible working diaphragm 1^a preferably made of rubber or other comparable material and arranged to reciprocate between the two opposed inner faces of the main chamber 1. Formed integral with the casting 3 and extending upwardly therefrom is a valve casing 6 provided with a transverse cylindrical conduit 7, communicating with the main chamber 1 through a central passageway 8. Extending upwardly from the ends of the conduit 7 is slurry inlet 9 and a slurry outlet 11 arranged for communication respectively with the open ends of the conduit 7 through passageways 12 and 13.

Formed on either end of the casing 6 are inlet and outlet diaphragm valves 14 and 15 for alternately opening and closing the opposed ends of the conduit 7. Each of these valves comprises a flexible rubber diaphragm 16 clamped between a ring or boss 17 formed in the valve casing 6 and a dished valve cap 18. For purposes of identification, the diaphragm 16 operatively associated with the passageway 12 may be referred to as an "inlet diaphragm," and the opposed diaphragm 16 associated with the outlet diaphragm as an "outlet diaphragm." In effect, these diaphragms constitute gates and therefore may be further qualified as "diaphragm gates."

Communication between the chamber defined

by the working diaphragm 1^a and the casting 2 and a suitable source of fluid pressure is established by the conduit 19, a cross 21, a conduit 22, a solenoid-valve 23, and a conduit 24. The diaphragm valve 14 is connected with the same source of fluid pressure by a conduit 25, the solenoid-valve 23 and the conduit 24. Communication between the diaphragm valve 15 and source of fluid pressure is established by a conduit 26, a solenoid-valve 27, a conduit 28, and the lower section of the conduit 24.

The solenoid-valves 23 and 27 may be of standard construction and comprise a central chamber 29 and lateral chambers 31 and 32, communicating therewith through valve ports controlled by the valves 33 and 34. The valves 33 and 34 are carried at the ends of a common valve stem 35, actuated by a solenoid 36. When the valve stem is seated in its lowermost position, communication between its associated diaphragm valve and the source of fluid pressure is cut off, and communication between the outer chamber of the diaphragm valve and atmosphere is established through the central chamber 29, the lateral chamber 34, and a vent 37 formed therein.

The solenoids 36 are connected through electric circuits 38 and a time switch or program clock 39 with a source of current 41. By means of the clock 39, the two solenoids may be made to operate successively in any predetermined cycle alternatively to positively open and close the inlet and outlet diaphragm valves 14 and 15, and to periodically operate the working diaphragm 1^a of the main pump chamber.

Connected to the cross 21 through a valve 42 is a pressure gauge 43, which may be used to determine the pressure under which the valve is being operated.

Shunted across the circuit 38 is an electric counter 44 for continuously recording the number of strokes made by the pump.

The cycle of operation of a pump made in accordance with the above description is as follows:

As shown in the drawing, the working diaphragm 1^a has completed its exhaust stroke, the inlet diaphragm valve 14 is closed, the outlet diaphragm valve 15 is open, and the pump or slurry previously filling the main pump chamber 1 has been expelled outwardly through the passageways 8 and 13, and the slurry outlet 11. The program clock 39 then reverses the respective positions of solenoid-valves 23 and 27, thereby permitting the escape of air or other fluid working medium from the inlet diaphragm valve 14, and from the under side of the pump diaphragm 1^a.

through the conduits 25 and 22, through the central chamber 29 of the solenoid-valve 23, through the lower lateral chamber 32, and through the vent 31. Slurry then, under the action of gravity or other force, enters the inlet 9, traveling through the passageway 12, through the left end of the conduit 1, and the passageway 8, into the main pump chamber. In the meantime, air entering the upper chamber 33 of the solenoid-valve 21, and passing through the open valve 33 and the conduit 26, has forced the diaphragm 16 of the outlet diaphragm valve 15 in sealing engagement with the left end of the conduit 1. In the uppermost position of the valve stem 35, the valve 34 is closed, thereby preventing the escape of air through the vent 31. The discharge stroke of the pump is then effected by reversing the positions of the solenoid-valves to the position shown in the drawing and already described.

Although in the pump as above described, gravity alone has been relied upon for filling the pump, vacuum can be used for this purpose by connecting the vent 31 to a source of vacuum on the intake stroke of the pump.

By resorting to positively actuated diaphragm valves for controlling the cycle of operation of the pump, the pump can be used with a higher degree of accuracy as a metering pump than can pumps utilizing conventional check valves which depend on the direction of travel of the pulp or slurry within the pump for their action.

It should be particularly noted that the solenoid-valve 23 controls the operation of the working diaphragm 1^a as well as the operation of the inlet diaphragm valve 14. However, a separate solenoid-valve can be used to control the working diaphragm 1^a, thereby permitting the separate timing of the valve 23 and insuring the closing of the inlet valve 14 before the working diaphragm 1^a begins to operate.

I claim:

1. A pump comprising: a slurry chamber; a working diaphragm sealed across said chamber and arranged for reciprocation therein; slurry inlet and outlet conduits communicating with said chamber; inlet and outlet diaphragm gates respectively associated with said inlet and outlet conduits; and solenoid-operated time-controlled fluid means for actuating said working diaphragm and said inlet and outlet diaphragm gates in a cycle wherein when said working diaphragm is making its discharge stroke, said inlet diaphragm gate is in its closed position and said outlet diaphragm gate is in its open position, and wherein when said working diaphragm is making its intake stroke, the positions of said gates are reversed.

2. A pump comprising: a slurry chamber; a

working diaphragm sealed across said chamber and arranged for reciprocation therein; slurry inlet and outlet conduits communicating with said chamber; inlet and outlet diaphragm gates respectively associated with said inlet and outlet conduits; solenoid-controlled fluid means for simultaneously actuating said working diaphragm and inlet diaphragm gate; and independent solenoid-controlled fluid means for actuating said outlet diaphragm gate, the operation of said gates and said working diaphragm being so correlated that when said working diaphragm is effecting its discharge stroke, said outlet gate is in its open position and said inlet gate is in its closed position, and when said working diaphragm is effecting its intake stroke, said inlet gate is in its open position and said outlet gate is in its closed position.

3. A pump comprising: a pump body divided by a working diaphragm into a slurry chamber and a working chamber; inlet and outlet conduits communicating with said slurry chamber; inlet and outlet diaphragm gate valves associated respectively with said inlet and outlet conduits; a first conduit establishing communication between said working chamber and said inlet diaphragm gate valve; a fluid pressure line communicating with said first conduit; a second conduit establishing communication between said outlet diaphragm gate valve and said fluid pressure line; a first valve interposed in said fluid pressure line at a point between its junctions with said first and second conduits; a second valve interposed intermediate the ends of said second conduit; and time-controlled means for alternately opening and closing said first and second valves in opposed sequence.

4. A pump comprising: a pump body divided by a working diaphragm into a slurry chamber and working chamber; inlet and outlet conduits communicating with said slurry chamber; inlet and outlet diaphragm gate valves associated respectively with said inlet and outlet conduits; a first conduit establishing communication between said working chamber and said inlet diaphragm gate valve; a fluid pressure line communicating with said first conduit, a second conduit establishing communication between said outlet diaphragm gate valve and said fluid pressure line; a first valve interposed in said fluid pressure line at a point between its junctions with said first and second conduits; a second valve interposed intermediate the ends of said second conduit; a first solenoid for operating said first valve; a second solenoid for operating said second valve; and time-controlled means for alternately energizing said solenoids.

ELMER H. HERBERT.

CERTIFICATE OF CORRECTION.

Patent No. 2,383,193.

August 21, 1945.

ELMER H. HERBERT.

It is hereby certified that the name of the assignee in the above numbered patent was erroneously described and specified as "Oliver United Filters Incorporated" whereas said name should have been described and specified as --Oliver United Filters Incorporated--, as shown by the record of assignments in this office; and that the said Letters Patent should be read with this correction therein that the same may conform to the record of the case in the Patent Office.

Signed and sealed this 5th day of February, A. D. 1946.

Leslie Frazer
